[57] **CLAIM**

The ornamental design for a link element, as shown and described.

DESCRIPTION

FIG. 1 is a front elevational view of a link element showing my new design;

FIG. 2 is a bottom plan view;

FIG. 3 is a left side elevational view;

FIG. 4 is a vertical sectional view taken along lines 4—4 of FIG. 2;

FIG. 5 is a rear elevational view;

FIG. 6 is a sectional view taken along lines 6—6 in FIG. 1;

FIG. 7 is an exploded sectional view taken along the lines 7—7 in FIG. 8, with each element disconnected;

FIG. 8 is an exploded front elevational view; and

FIG. 9 is a reduced front elevational view of a circular supporting member.

The broken line showing of a circular supporting member in FIG. 9 is for illustrative purposes only and forms no part of the claimed design.
